UNITED STATES PATENT OFFICE.

ELLIS M. TREAT, OF BUFFALO, NEW YORK.

SEPULCHER.

1,240,106.

Specification of Letters Patent. Patented Sept. 11, 1917.

Application filed December 21, 1916. Serial No. 138,243.

To all whom it may concern:

Be it known that I, ELLIS M. TREAT, a citizen of the United States, residing at Buffalo, in the county of Erie and State of New York, have invented certain new and useful Improvements in Sepulchers, of which the following is a specification.

This invention relates to sepulchers and has special reference to an underground concrete sepulcher.

Sepulchers have been constructed of concrete and have had metal linings both in the body and the top but I have found that such sepulchers were defective even when the metal top was soldered to the body lining, the defects being in part due to the fact that the top lining was not interlocked with the metal part of the body so that the soldered joint would spring and leak.

One important object of the invention is, therefore, to so improve the construction of sepulchers of this description that the joint between the metal portion of the top and body will be an interlocking joint throughout and will be so constructed as to receive and retain the solder.

Another defect existing in the usual construction of sepulchers resides in the fact that, even after sealing with solder and concrete the top can be separated from the body with practically no difficulty.

A second important object of the invention is, therefore, to so interlock the top and body with a metallic interlock that only by the destruction of the sepulcher can access be had to the interior whereby the remains interred may be kept inviolable.

Furthermore, in the usual construction of sepulchers, as above referred to, any defect in soldering which does not hold the metal parts of the top and body permits access of moisture to the sepulcher and the passage of any gases due to decomposition therefrom.

A third object of the present invention is to so improve the construction of sepulchers as to provide a continuous interlocking joint, uniting all parts of the upper edge of the metallic part of the body with the metallic part of the top, so constructed that the joint will form a substantially U-shaped trough whereinto solder may be poured and thus eliminate the possibility of any gaps or holes being left which would permit the passage of moisture or gas whereby the remains are preserved free from extraneous moisture and the sepulcher is thoroughly sanitary.

With the above and other objects in view, as will be hereinafter set forth, the invention consists in general of certain novel combinations of parts and arrangements of details hereinafter fully described, illustrated in the accompanying drawings and particularly claimed.

In the accompanying drawings like characters of reference indicate like parts in the several views, and:—

Figure 1 is a vertical longitudinal section of a sepulcher constructed in accordance with this invention.

Fig. 2 is a transverse section thereof.

Fig. 3 is an enlarged detail cross section particularly showing the interlocking joint and the arrangement of the arch forms to permit springing the parts of the joint together.

Fig. 4 is a detail perspective view of certain of the arch forms.

Fig. 5 is a perspective view of the body of the sepulcher before the top is applied thereto.

In the construction of a sepulcher the body is first made by casting in suitable forms an outer shell 10 of concrete. In this outer shell is fitted a lining 11 of copper or other suitable material having a high degree of resistance to corrosion under the conditions to which it is subjected. The upper edge of this lining projects above the shell and is turned inward throughout its entire length to form an inverted U-shaped flange 12. The body is then completed by forming within the lining of the outer shell an inner shell 13, the top edge of which is substantially level with the outer shell.

The forming of this body may be accomplished either *in situ* or at a distance from the grave, the body of the sepulcher being, in the latter case, transported to the place of burial and set in position.

On the top edge of the inner shell are then positioned the extremities of the transverse arch forms 14 and longitudinal ties 15, the latter serving to hold the arch forms in proper spaced relation. It is here to be particularly noticed that these parts are of such lengths that spaces are left between their ends and the upper edge portion of the metallic part of the body. The purpose of this will be presently brought out.

In order to provide for covering the body a top lining of sheet copper or the like is pressed to shape to provide a body portion

16 arched both longitudinally and transversely to fit the arch forms 14 which, it will be noted, are graduated in depth from the middle downward toward both ends as 5 well as provided with curved upper edges. Furthermore the pressing of this top lining is of such character as to provide a depending peripheral flange 17 having its bottom edge curved out and up to form a U-shaped 10 trough 18. The outside dimensions over all of this top lining are greater than the inside dimensions of the flanged part of the metal portion of the body so that, in order to bring the parts together it is necessary to spring 15 the flange 17 of the top inward and downward and it is to permit this springing that the ends of the top forms and ties terminate in the spaced relation to the metal of the body. The natural resiliency of the metal 20 causes the flange 17 to spring out again after this operation so that the parts assume the interlocked position best seen in Fig. 3.

After this operation is completed the trough 18 is filled with a suitable molten 25 solder 19 and, since the solder is received in a trough, this solder will spread out and completely seal the joint throughout its entire extent.

Now, with this solder in position and 30 solidified there is no way to spring the joint apart but the metallic portion of the sepulcher becomes substantially an integral sheet.

In order to protect the top it is preferred to cover it entirely with a layer of concrete 35 20. When this is done the sepulcher is not alone hermetically sealed but only by violent attack can any part be separated from another since it is necessary to cut away both concrete and metal.

40 In order to additionally reinforce the joint and assist in preventing access of moisture the top may be connected to the body portion by a tongue and groove joint 21, which allows perfect seating of the top to 45 the body, and a filling of cement therebetween.

It will be noted that, while the concrete has been shown in the present drawings without any other reinforcement than that 50 afforded by the metallic body and top portions, yet the construction will apply equally well and without change to concrete which is reinforced. I have not deemed it necessary to show any reinforcing; however, as 55 the same is old and well known.

It will also be noted that the thickness of this concrete top removes any danger of

breaking down due to the dropping of earth and stones upon it when filling in a grave. Furthermore, this instance is enhanced by 60 reason of the fact that the concrete top rests tightly on the metal top which in turn is thoroughly supported from beneath by the wooden arch members and the sides of the body. 65

There has thus been provided a highly efficient construction of the kind described and for the purpose specified.

It is obvious that minor changes may be made in this construction without departing from the principles involved therein. It is not therefore desired to confine the invention to that shown and specifically described, but it is wished to include all such as properly come within the scope claimed. 70 75

Having thus described the invention, what is claimed, is:—

1. A sepulcher having a metallic body portion provided with an inwardly and downwardly turned flange along its entire 80 upper edge, and a top for said body having a depending flange provided with an outwardly and upwardly turned edge constituting a continuous trough and interlocking with the flange of the body. 85

2. A sepulcher having a metallic body portion provided with an inwardly and downwardly turned flange along its entire upper edge, a top for said body having a depending flange provided with an outwardly and upwardly turned edge constituting a continuous trough and interlocking with the flange of the body and a filling of 90 solder in said trough. 95

3. A sepulcher having a metallic body portion provided with an inwardly and downwardly turned flange along its entire upper edge, a top for said body having a depending flange provided with an outwardly and upwardly turned edge constituting a continuous trough and interlocking with the flange of the body, an outer shell 100 of concrete substantially surrounding the body but terminating short of the flange, an inner shell of concrete within the body, and a covering of concrete over said top and inclosing the interlocking joint between the top and body. 105

In testimony whereof I affix my signature in the presence of two witnesses:

ELLIS M. TREAT.
